UNITED STATES PATENT OFFICE.

SAMUEL J. SILBERMAN, OF NEW YORK, N. Y.

TAG.

SPECIFICATION forming part of Letters Patent No. 644,373, dated February 27, 1900.

Application filed October 25, 1899. Serial No. 734,758. (No model.)

To all whom it may concern:

Be it known that I, SAMUEL J. SILBERMAN, of the city of New York, borough of Manhattan, in the county and State of New York, 5 have invented a new and Improved Clothing-Tag, of which the following is a full, clear, and exact description.

The purpose of this invention is to provide a tag for identifying clothing before it passes 10 from the manufacturer and also to so arrange this tag that it may be applied to the article of clothing to fully expose the tag, and yet permit of its easy disconnection from the clothing.

This specification is the disclosure of one 15 form of my invention, while the claims define the actual scope thereof.

Reference is to be had to the accompanying drawings, forming a part of this specification, in which similar characters of reference indicate 20 corresponding parts in all the views.

Figure 1 is a perspective view of a tag, showing the fastener applied. Fig. 2 is a detached perspective view of the fastener. Fig. 3 is a view illustrating the manner of attaching the 25 tag to one of the sections of cloth. Fig. 4 is a view illustrating the manner of applying the other section of cloth and of sewing the two. Fig. 5 is a view showing the cloth after it has 30 been sewed and illustrating the detachment of the tag therefrom, and Fig. 6 is a section showing the tag attached to the cloth when sewed.

The tag *a* may be of any desired character, except that it should be constructed of paper 35 or other substance easily torn. The fastener for the tag is of the peculiar form illustrated in Fig. 2 and comprises a triangular head *b*, from each corner of which projects a prong *c*. If desired, less than three prongs may be used.

40 These prongs are passed through the tag *a*, as shown in Fig 1, so that the head *b* lies snugly against the tag. The advantage of this triangular fastening device is that one of the three prongs *c* may be engaged with the cloth-sections *e*, Fig. 3, at a point directly adjacent to the edge thereof, thus leaving sufficient space usually occupied for width of seam without interfering with the metal fastener in sewing, the other two prongs *c* serving as guides 45 or gage-prongs which are abutted against the edge of the cloth to determine the relative position of the first-mentioned prong or that

which pierces the goods. When the prongs have been arranged as shown in Fig. 3, the several prongs are bent inward, causing them 55 to lie over each other, as shown in Fig. 4, and to bear down on the cloth to securely hold the tag thereto. It will be observed that this arrangement securely attaches the tag to the cloth at the very edge of the cloth and avoids 60 puncturing and otherwise injuring the body thereof.

Now in attaching this tag to the article of clothing the section *e* of the cloth which carries the tag is made to compose one part of 65 the cloth of the garment. Another part *f* of the cloth of the garment is laid against the part *e* and the two are sewed together in the usual manner by a line of stitching *g*. The parts *e* and *f* are so laid that the tag *a* is placed 70 between them, and the line of stitching *g* is therefore passed directly through the tag at a point adjacent to the fastening device thereof. This serves to score or puncture the card. The pieces of cloth *e* and *f* being now sewed 75 together are laid open, as shown in Figs. 5 and 6, and the seam is pressed in the manner well understood. This has the result of completely exposing the body of the tag *a* and yet of holding the same securely by means of the fastening device which is in the inside of the seam and at the front edge of the cloth-sections *e* and *f*. Now when it is desired to sever the tag from the article of clothing the body or exposed portion of the tag is simply grasped 80 and torn downward, as indicated in Fig. 5, it being understood that the line of stitching *g*, having scored or punctured the card, renders this operation very easy. The result is that the tag is torn from the clothing, so as to 85 be no longer visible, and the cloth is in no way injured by the fastening device. It should be understood that the inner extremity of the tag, which extremity bears the fastening device, remains with the fastening device inside 90 the seam of the garment, where, of course, it is invisible and can work no harm.

Having thus described my invention, I claim as new and desire to secure by Letters Patent—

1. As a new article of manufacture, a sewed article, comprising two cloth-sections united by a seam, and a tag situated between the cloth-sections and held in place by the seam,

thus securing the tag and perforating it at the seam so that the exposed portion of the tag may be readily torn from the part inside the seam.

5 2. As a new article of manufacture, a sewed article, comprising two sections of cloth united by a seam, a tag situate between said sections of cloth and held in place by the seam, and a

fastening device joining the inner end of the tag with the edge of one of the cloth sections to inside of the seam.

SAMUEL J. SILBERMAN.
